UNITED STATES PATENT OFFICE.

JOHN F. WING, OF CHICAGO, ILLINOIS, ASSIGNOR, BY MESNE ASSIGNMENTS, TO
CONTINENTAL CAN COMPANY, INC., A CORPORATION OF NEW YORK.

CAN-CLOSING MACHINE.

1,132,295.

Specification of Letters Patent. Patented Mar. 16, 1915.

Application filed April 7, 1911. Serial No. 619,587.

To all whom it may concern:

Be it known that I, JOHN F. WING, a citizen of the United States, residing at Chicago, in the county of Cook, State of Illinois, have invented certain new and useful Improvements in Can-Closing Machines, of which the following is a description, reference being had to the accompanying drawing, and to the letters and figures of reference marked thereon.

The invention relates to new and useful improvements in can closing machines, and more especially to machines of this type for attaching a can end or can cover to a filled can body.

An object of the invention is to provide mechanical means for feeding a can end from a stack underneath a seaming head, whereby the same is placed for attachment to the can body.

A further object of the invention is to provide means for rendering said feeding-in means ineffective, except when a can body is underneath the seaming head.

These and other objects will in part be obvious, and will in part be hereinafter more fully described.

In the drawings which show by way of illustration one embodiment of the invention,—Figure 1 is a side view of a closing machine having my improvements applied thereto; Fig. 2 is a plan view of the supporting plate for the stack of can ends, and the devices for operating the pusher to feed in the can ends; Fig. 3 is a similar plan view with the devices for operating the pusher broken away, and the controlling means for rendering the feeding-in device ineffective, shown in top plan; Fig. 4 is a detail view, showing the stack holder and the finger for rendering the pusher ineffective; Fig. 5 is a sectional view on the line 5—5 of Fig. 4; Fig. 6 is an enlarged view in side elevation, showing the controlling device for the feeding-in mechanism, with the parts in position to render the feed effective; Fig. 7 is a similar view with the parts in position to render the feed ineffective; and Fig. 8 is a detail showing a modified construction of the controlling pad.

The can closing machine herein shown consists generally of a frame 1, in which is mounted a seaming head 2, consisting of the usual seaming rollers for curling the flange

on a can end or cover, so as to form a double seam. The seaming head 2 is mounted on a shaft 3, which is rotated by a bevel gear connection 4 from a cross shaft 5, which in turn is operated from the main shaft of the machine. This seaming head is moved up and down by a lever 6.

The can bodies which are to be closed are mounted on a support 7, and are fed along the same by a drum feed 8, which consists of a drum having a thread wound thereon, which thread extends above the support and engages the lower ends of the can bodies. The filled can bodies are carried by means of this feed underneath the seaming head, and the seaming head is lowered, so as to bring the seaming rolls into proper position to act upon the cover or end to secure the same to the can body.

Extending underneath the seaming head is a supporting and centering plate 9, which is mounted to move up and down in a bracket 10 secured to the frame 1 of the machine. The supporting and centering plate is attached to a rod 11, which is in turn connected to a lug on the lever 6. As the seaming head moves up and down, this supporting and centering plate will move up and down with the seaming head. Said plate is positioned a sufficient distance below the seaming head so as to allow the seaming head to rotate and the seaming rolls to be brought into contact with the flange on the can end to roll the same into a double seam.

Centrally of the supporting plate is an opening 12, which extends over the can body and serves to center the same underneath the seaming head. Mounted on the supporting plate 9 is a holder 13 for a stack of can ends. Said holder consists of a base plate 14, and a series of rods 15, which hold the can ends stacked one above the other. A pusher 16 slides through a suitable recess underneath the base 14, and is adapted to engage the lower can end in the stack and carry the same along a guiding raceway to a supporting ledge 17, surrounding the opening 12 and forming a seat for centering the can end underneath the seaming head. The cover rests on this supporting ledge, and as the plate 9 is moved downward, the cover will be carried on to the can body, and will be seated therein by the usual seating pad, after which it is engaged by the chuck, so

as to hold the can body stationary while the seaming head rotates about the same to secure the can end on to the can body.

The pusher 16 is provided adjacent its outer end with a post 18. To the upper end of this post is pivoted a link 19, which is in turn pivoted to a rock lever 20 attached to the frame 1 of the machine. The other end of the rock lever 20 is connected to a link 21, which in turn is pivoted to a stud 22 that is radially adjustable in a disk 23 mounted on a cross shaft of the machine.

The link 19 is preferably made in sections, which are connected together by a sleeve 24, so that the length of the link 19 may be varied to vary the working position of the feeding-in pusher. As the cross shaft carrying the disk 23 rotates with the seaming head, the rock lever 20 will be oscillated, and said lever through the link 19 will reciprocate the pusher so that a can end will be taken from the stack and placed on the supporting ledge at each reciprocation of the pusher. The stud 22 may be adjusted radially on the disk 23, so as to vary the stroke of the pusher. By this adjustment and the adjustment of the link 19, I am able to control the stroke of the pusher, so that can ends of different sizes may be fed to the seaming head and properly positioned centrally underneath the same.

With the above mechanical means for feeding in the can ends, it will be noted that a can end is fed to the seaming head for each reciprocation of the seaming head. In order to prevent the feeding in of can ends when there is no can body underneath the head to receive the can end, I have provided a controlling means for rendering the feeding-in devices effective or ineffective, in accordance with whether can bodies are being fed to the seaming head. Said controlling means, as herein shown, consists of a finger 25, which is mounted so as to slide back and forth in a supporting bracket 26 attached to the supporting plate 9. This finger projects through the base 14 into the stack holder, so that the lower can end in a stack will rest at one side on said finger. The finger is so disposed relative to the pusher 16, that when said finger is at the inner end of its stroke, as shown in Figs. 4 and 5, the can ends will be raised so that the pusher will move underneath the can ends without engaging the lower can end in the stack, and, therefore, when the finger is at the inner end of its stroke, said feeding-in means will be ineffective.

The finger 25 is moved back and forth by a plunger 27, which is formed at its lower end with a vertical portion 28, and an inclined portion 29. These parts 28 and 29 are adapted to move in an opening 30 in the finger 25. It will readily be seen, therefore, that when this plunger is moved from

the position shown in Fig. 5 to its extreme upper position, that the finger 25 will be withdrawn from the stack holder sufficiently to allow the stacked can ends to descend and the lowermost end to be placed in the path of movement of the pusher. When the plunger is moved again to the position shown in Fig. 5, the finger will be moved into the stack holder.

The inner end of the finger 25 is tapered at 31, so as to aid in lifting the stack or in passing underneath the lowermost end in the stack. A plate 32 is secured to the upper face of the pusher 16 on the side thereof adjacent the finger 25, to aid in holding the stacked ends so that the finger 25 may be with certainty moved underneath the same to support the ends at one side thereof.

The plunger 27 is provided with two spaced collars 33, which are fixed thereto. A lever 34 is pivoted at one end to a bracket 35, and is formed with a ball collar 36 intermediate its ends, which rests between the fixed collars 33 on the plunger 27. The lever 34 at its outer end is pivoted at 37 to a controlling pad 38. A weight 39 is secured to the lever 34. It is obvious, however, that in place of said weight any desired means may be used for depressing the outer end of the lever 34. The controlling pad 38 is positioned so as to extend over the filled can on the feeding device, which is to be carried underneath the seaming head for the next succeeding action of the seaming head.

In the operation of my device, as the pusher 16 is moved back and forth, the can ends in the stack holder are normally held out of the path of the pusher, so that the feeding-in means is ineffective. When a filled can is brought along the support 7 to a point within the path of the controlling pad 38, the next downward movement of the seaming head, which carries with it the supporting plate 9, the stack holder and the feeding-in devices, as well as the controlling finger, will cause the controlling pad to engage the top of the can body, which will limit the downward movement of the outer end of the lever 34. The further downward movement of the plate 9 will cause the lever 34 to swing about its fulcrum on the bracket 35 and lift the plunger 27, which will withdraw the finger 25 from the stack holder and allow the lowermost can end in the stack holder to drop into the path of movement of the pusher. The forward movement of the pusher will carry the can end on to the supporting ledge 17, and in position to be placed on the can body which controls the delivery of the can end as it is carried under the seaming head, and the seaming head moves down to close the same.

If a series of filled can bodies follow one after another along the support 7, the con-

trolling means will operate at each movement of the seaming head to allow a can head to be engaged and moved on to the supporting ledge 17. If, however, the operator fails to position the can body on the feeding-in mechanism, so that during one operation of the seaming head no can body is present to be closed, then the controlling pad 38 will move down with the plate 9, as 10 there is no can body in the path of movement of the controlling pad, and the finger will not be released from the stack holder. The finger 25 is returned to its normal position supporting the ends in the stack holder 15 by the weight 39.

It is sometimes desirable to depress the floating contents of a filled can prior to the placing of the can end on the same. In order to accomplish this depressing of the 20 contents, I may form the controlling pad 38 with a downwardly projecting center portion 40, which substantially fits the inner side of the filled can, and will depress the floating contents into the can body. Said 25 controlling pad is provided with a ledge 41, which engages the edge of the can body and limits the downward movement of the pad so as to operate the controlling finger.

It is obvious that minor changes in the 30 details of construction may be made, without departing from the spirit of my invention, as set forth in the appended claims.

Having thus described my invention, what I claim as new and desire to secure by Letters Patent, is:—

1. A can closing machine including in combination a can body support, a seaming head, a support for can ends extending between the seaming head and the can body support and held in fixed relation to said seaming head, means for giving the seaming head and can body support a relative movement for causing the can body and can end to engage said seaming head, a 40 stack holder, a pusher mounted on said can end support for engaging a can end in the stack holder and moving the same underneath the seaming head, means for reciprocating said pusher in unison with the relative movements of the seaming head and the can body support whereby a can end may be moved underneath said seaming head when the same is out of contact with the can body, and means controlled by the can bodies for rendering the feeding action of the pusher ineffective to feed the can ends, except when a can body is fed underneath said seaming head.
2. A can closing machine including in combination a can body support, a rotating seaming head having seaming rolls, a support for the can ends extending between the seaming head and the can body support and held in fixed relation to said seaming head, means for giving said can body support and
3. A can closing machine including in combination a can body support, a rotating seaming head having seaming rolls, a support for the can ends extending between the seaming head and the can body support and held in fixed relation to said seaming head, a seat adjacent said opening for centering the can ends relative thereto, means for feeding the can ends on to said can end support at a point outside of the seaming head, a pusher for engaging the can ends and feeding the same along the can end support on to said seat, and means for reciprocating said pusher in time with the relative movements of the seaming head and can end support whereby a can end may be moved underneath the seaming head when the same is out of contact with the can body.
4. A can closing machine including in combination, a can body support, a rotating seaming head having seaming rolls located above said can body support, a support for can ends extending between the seaming head and the can body support and held in fixed relation to the seaming head, said can end support having an opening therethrough the center of which is in line with the axis of the rotating head, said can end support having a seat for the can ends for centering the same relative to said opening, means for feeding can ends on to said can end support at a point outside of the seaming head, a pusher for engaging the can ends and feed-

said seaming head a relative movement for causing the can body to engage the can end on the can end support and for causing the can end and can body to engage said seaming head, said can end support having an opening therethrough, the center of which is in line with the axis of the rotating head, a seat adjacent said opening for centering the can ends relative thereto, means for feeding the can ends on to said can end support at a point outside of the seaming head, a pusher for engaging the can ends and feeding the same along the can end support on to said seat, and means for reciprocating said pusher in time with the relative movements of the seaming head and can end support whereby a can end may be moved underneath the seaming head when the same is out of contact with the can body.

3. A can closing machine including in combination a can body support, a rotating seaming head having seaming rolls, a support for the can ends extending between the seaming head and the can body support and held in fixed relation to said seaming head, means for giving said can body support and said seaming head a relative movement for causing the can body to engage the can end on the can end support and for causing the can end and can body to engage said seaming head, said can end support having an opening therethrough, the center of which is in line with the axis of the rotating head, a seat adjacent said opening for centering the can end relative thereto, means for feeding the can ends on to said can end support at a point outside of the seaming head, a pusher for engaging the can ends and feeding the same along the can end support on to said seat, means for reciprocating said pusher in time with the relative movements of the seaming head and can end support whereby a can end may be moved underneath the seaming head when the same is out of contact with the can body, and means controlled by the can bodies fed to the closing machine for rendering the pusher ineffective in its feeding action except when a can body is fed underneath the seaming head for said can end.

4. A can closing machine including in combination, a can body support, a rotating seaming head having seaming rolls located above said can body support, a support for can ends extending between the seaming head and the can body support and held in fixed relation to the seaming head, said can end support having an opening therethrough the center of which is in line with the axis of the rotating head, said can end support having a seat for the can ends for centering the same relative to said opening, means for feeding can ends on to said can end support at a point outside of the seaming head, a pusher for engaging the can ends and feed-

ing the same along said can end support on to said seat, means for reciprocating the pusher and means controlled by the can bodies fed to the closing machine for rendering the pusher ineffective in its feeding action except when a can body is fed underneath the seaming head for said can end.

5. A can closing machine including in combination, a can body support, a continuously rotating seaming head, seaming rolls carried thereby, a support for can ends extending between the seaming head and the can body support, said support being held from rotation and in fixed vertical relation to the seaming head, said can end support having an opening therethrough, the center of which is in line with the axis of the rotating head and a seat for the can ends for centering the same relative to said opening, 10 means for feeding can ends on to said seat, and means controlled by the can bodies fed to the closing machine for rendering the feeding means ineffective in its feeding action except when a can body is fed underneath the seaming head for said can end.

6. A can closing machine including in combination, a can body support, a seaming head, means for moving the seaming head relative to said support, a support for a can end movable with said seaming head, a stack holder carried by said movable support, a pusher for engaging a can end in said stack holder and moving the same underneath the seaming head, and means operating in unison with the seaming head for moving said pusher, said means including an adjustable link, whereby the working position of the pusher may be varied.

7. A can closing machine including in combination, a can body support, a seaming head, means for moving the seaming head relative to said support, a support for a can end movable with said seaming head, a stack holder carried by said movable support, a pusher for engaging a can end in said stack holder and moving the same underneath the seaming head, and means operating in unison with the seaming head for moving said pusher, said means including a disk having 45 a radially adjustable stud, whereby the throw of the pusher may be varied.

8. A can closing machine including in combination, a can body support, a seaming

head, means for moving the seaming head relative to said support, a support for a can end movable with said seaming head, a stack holder carried by said movable support, a pusher for engaging a can end in said stack holder and moving the same underneath the seaming head, and means operating in unison with the seaming head for moving said pusher, said means including an adjustable link, whereby the working position of the pusher may be varied, and a disk having a radially adjustable stud, whereby the throw of the pusher may be varied.

9. A can closing machine including in combination, a seaming head, a supporting plate movable with said seaming head, a stack holder on said supporting plate, a pusher for engaging a can end in the stack holder and moving the same underneath the seaming head, a finger for normally supporting the can ends in the stack holder out of the path of the pusher, a lever for withdrawing said finger from the stack holder, and a controlling pad carried by the lever for engaging a can body to operate the lever on the downward movement of the supporting plate.

10. A can closing machine including in combination, a can body support, means for feeding can bodies along said support, a seaming head movable toward and from said support, a supporting plate movable with said seaming head, a stack holder carried by said supporting plate, a pusher on said plate for engaging a can end in the stack holder and moving the same underneath the seaming head, a finger extending into said stack holder for normally supporting the ends out of the path of the pusher, a plunger having a positive engagement with said finger for moving the same back and forth, a lever connected with said plunger and fulcrumed on said movable plate, a controlling pad connected to the outer end of said lever and located directly over the feeding devices for the filled cans.

In testimony whereof I affix my signature, in presence of two witnesses.

JOHN F. WING.
